UNITED STATES PATENT OFFICE.

EDWARD ZINIKER, OF EUGENE, OREGON.

DESIGN FOR A GARDEN FOUNTAIN.

Application filed July 1, 1922. Serial No. 2,913. Term of patent 14 years.

To all whom it may concern:

Be it known that I, EDWARD ZINIKER, a citizen of Switzerland, residing at Eugene, in the county of Lane and State of Oregon, have invented a new, original, and ornamental Design for a Garden Fountain, of which the following is a specification, reference being had to the accompanying drawing, forming a part thereof.

The figure is a perspective view of my garden ornament, showing my design.

I claim:

The ornamental design for a garden fountain, as shown.

EDWARD ZINIKER.
